LINO SCUSA, OF PHOENIX, NEW YORK.

INTERNAL GAGE.

1,318,697.

Specification of Letters Patent. Patented Oct. 14, 1919.

Application filed March 12, 1919. Serial No. 282,146.

To all whom it may concern:

Be it known that I, LINO SCUSA, a citizen of the United States, residing at Phoenix, in the county of Oswego and State of New York, have invented certain new and useful Improvements in Internal Gages, of which the following is a specification.

This invention relates to improvements in gages, and has for its object to provide a 10 novel and simple adjustable tool of the class, which is adapted for use as a master gage, by which other gages may be set, verified and corrected, as well as for the ordinary gage work. A further object is to provide 15 an adjustable gage which is particularly adapted for gaging internal work, such as slots and grooves, as well as for gaging the distance between the points of limit or snap gages. And a further object is to provide 20 an internal limit gage, wherein a plurality of alining gage bolts are adjustably fitted in a suitable body, the bolts at one end of the body being rigidly set, while the bolts at the opposite end are adjustable toward 25 and away from the rigid bolts, for varying the range and latitude of the gage.

I attain these objects by the means set forth in the detailed description which follows, and as illustrated by the accompanying 30 drawing, in which—

Figure 1 is a side view, partially in section, the latter being taken substantially on line 1—1 of Fig. 3. Fig. 2 is an end view; showing the fixed gage bolts. Fig. 3 is a 35 similar view of the opposite end, partially in elevation and partially in vertical cross-section, the latter being taken on line 3—3 of Fig. 1. Fig. 4 is an edge view of the gage. Figs. 5, 6 and 7 are respectively elevational views, of one of the fixed bolts; one of the adjusting screws, and one of the 40 adjustable bolts. Fig. 8 is a reduced side view of the gage; showing the use of the same for gaging the breadth or length of a slot or groove. Figs. 9 and 10 are respectively a side view, and a central vertical cross-section; showing a modified construction of the gage body.

In the drawing, referring to Figs. 1 to 4 45 inclusive, the body of the gage, which is preferably I-shaped, and made of cast iron, consists of similar T-heads 2 and 2', which are connected by an integral oblong bar or column 2^a. The head 2 is bored out for a 50 part of its breadth, to provide spaced parallel longitudinal sockets 3 and 4, in which

are preferably driven fixed gage bolts 3' and 4', the free ends of which preferably project an equal distance beyond and clear of the head 2, for facilitating gaging without interference from the body. The head 2' is also bored out longitudinally, as at 3^a and 4^a, to receive adjustable bolts 3^c and 4^c, which are disposed in line with and in alignment with the respective fixed bolts in head 56 60 2. The inner ends of the holes 3^a and 4^a are threaded to receive adjusting screws 3^d and 4^d, which are employed for moving the adjustable bolts outwardly away from the fixed bolts, and also for assisting in holding 70 them in the various adjusted positions. The screws 3^d and 4^d are operable by means of a screw-driver shown by dotted lines at α in Fig. 1. By providing the similar alining bolts 3'—3^c and 4'—4^c, the device may be 75 set for gaging both the rough cuts and the finished work. Or, the corresponding bolts may be set for gaging separate pieces of work of different dimensions, where no limit 80 is required.

In the preferred form of the device, the reciprocable bolts 3^c and 4^c are held rigidly in the adjustable position by means of similar locking members 5, each of which has oppositely facing conical portions 5', disposed between its cylindrical ends 5^a. The conical portions 5' are preferably disposed eccentric to the axes of the ends of said members. The locking members 5 are disposed in lateral sockets or holes 5^c, which pass through the head 2' and intersect with the holes 3^a and 4^a, as best seen in Figs. 1 and 3. In order to effect the rigid frictional engagement between the cones 5^a and the adjustable bolts, the latter are provided 90 with similar bevel or plane surfaces 6, which form dull V-teeth along one side of said bolts (see Figs. 1, 3 and 7). By arranging the cones 5^a eccentric to the sockets 5^c, it only requires a slight partial rotation of the 95 locking members to bring the cones into tight frictional engagement with the planes 6, for rigidly locking and holding the adjustable bolts against the adjusting screws 3^d—4^d. The locking members are preferably 100 operated by a screw-driver (not shown), which is received in slots 5^d, the slotted ends of said members being reversed, so that when said members are rotated clockwise, they tend to force and hold the inner 110 ends of the adjustable bolts tightly against the inner ends of the set-screws.

In Fig. 8 my gage is shown in connection with a piece of work 7 (shown by dotted lines), wherein the gage-bolts 3'-3^e are gaging the length or breadth of a slot 7', which may be understood to be the last or finish dimension of said slot; while the gage-bolts 4'-4^e, for example, had previously been set and used for gaging the first or rough cutting of the slot 7', as indicated by the dotted line 7^a.

Figs. 9 and 10 illustrate a slight modification of the construction of the gage body, wherein the bar or column 8, which connects the heads 2 and 2', is fluted, as at 8', for providing clearance for the insertion and operation of the screws 3^d and 4^d. A particular object of the fluted or concave column is to increase its strength, so as to prevent possible springing of the body while the gage is being used. This is an important provision, especially in the case of small gages, wherein the gage-bolts are disposed close together, which necessitates the narrowing of the neck or column 8, and rendering the same liable to spring when the gage is forced into close fitting work. By grooving the lateral edges of the column 8, the latter is adequately reinforced by increasing the breadth of the metal adjacent the top and bottom sides of the column. Otherwise, the arrangement, operation and locking of the gage-bolts of the modified structure are the same as shown in the preferred form of the device. The inner corners of one of the heads are beveled as at 10, to provide additional clearance for a screw-driver employed for operating the adjusting screws.

Having thus described my invention, what I claim, is—

1. In a gage, an I-shaped body having prominent T-heads, one of said heads provided with longitudinal sockets, the opposite head being bored out in alignment with said sockets, permanent gage bolts driven tightly into said sockets, adjustable gage bolts disposed in the bores of the opposite head, means for adjusting said adjustable bolts for gaging slots of different breadths, and means for locking said adjustable bolts in place.

2. In an internal gage, a plurality of adjustable gage bolts, an I-shaped body comprising similar T-heads connected by a relatively narrow column, one of said heads bored out to receive said adjustable bolts, the opposite head provided with sockets cor-

responding to and alining with said adjustable bolts, a gage bolt rigidly disposed in each of said sockets and projecting beyond the outer face of the head, and means for locking said adjustable bolts in different positions axially.

3. In an internal gage, a body comprising an oblong part provided at its opposite ends with similar T-heads, the corresponding projecting ends of said heads bored out to provide alining sockets for the reception of gage bolts, permanent gage bolts partially set in the sockets of one head, adjustable gage bolts correspondingly disposed in the sockets of the opposite head, screws for permitting the adjustment of the latter bolts toward and away from the permanent bolts, and means for locking said adjustable bolts in various adjusted positions.

4. In an internal gage, the combination with a plurality of permanent and adjustable gage bolts, of an oblong body having similar cross-heads which project laterally beyond the opposite edges of the body, one of said heads provided with spaced sockets whose axes are parallel to the opposite edges of said body adapted to receive said permanent bolts, the other head bored out in line axially with said sockets adapted to receive said adjustable bolts, and means for locking said adjustable bolts against rotation, as well as against longitudinal movement.

5. In an internal gage, an I-shaped body, its opposite ends comprising similar integral T-heads, the corresponding ends of said heads provided with axially alining sockets, permanent gage bolts disposed in the sockets of one head, reciprocable bolts disposed in the sockets of the other head, means for holding said reciprocable bolts from longitudinal movement in one direction, and means for locking said reciprocable bolts against longitudinal movement in the opposite direction and also for preventing the rotation of said bolts.

6. A body for internal gages, including an oblong portion having at its opposite ends similar cross-heads which project beyond its lateral edges, the projecting ends of both of said cross-heads provided with alining sockets, and the axes of the corresponding sockets of said cross-heads disposed beyond and parallel to the lateral edges of said oblong portion.

In testimony whereof I affix my signature,
LINO SCUSA.
